US0D1094878S

(12) **United States Design Patent** (10) Patent No.: **US D1,094,878 S**
(45) Date of Patent: ** Sep. 23, 2025

(54) **HAIR CARE APPLIANCE ACCESSORY**

(71) Applicant: **SharkNinja Operating LLC**,
Needham, MA (US)

(72) Inventors: **Daniel Van Alphen**, Lexington, MA
(US); **Ramsey Lehman**, Brookline, MA
(US)

(73) Assignee: **SharkNinja Operating LLC**,
Needham, MA (US)

(**) Term: **15 Years**

(21) Appl. No.: **29/922,868**

(22) Filed: **Dec. 26, 2023**
